[57] ABSTRACT

This invention relates to a current collecting roller, and more particularly a rotating current collecting roller for providing electric current to a high speed transportation apparatus. The roller comprises plural flexible planar or linear conductors with a liquid filled elastomer between the conductors. The elastomer is allowed to solidify thus forming an integral structure with the conductors.

CURRENT COLLECTING ROLLER

BACKGROUND OF THE INVENTION

Various current collecting devices are used at present as various power sources for producing driving power for travelling transportation systems. The most general one is current collection by stringing and pantograph, but the current collection using this system is limited at a speed of 350 Km/hr. due to vibration, the propagation speed of stringing, wear resistance of the stringing material, etc. To overcome these problems, an electric wire or current collecting line composed of a rigid conductor of a rail shape is fixed to the ground and the system uses a sliding contactor for collecting an electric current by contacting the conductor. When using a sliding rigid conductor or current collector fixed to a vehicle, the current collector jumps at the raised portion of the feeder line or current collecting line due to its geometrical irregularity and at the hard portion thereof based on the resilient irregularity. This jumping causes difficulty in maintaining good contact between the rigid current collector and the feeder line due to the vibration of the rigid current collector.

Another method is to slide a current collector, including linear conductors parallel to each other and perpendicular to a feeder line; and synchronization collector OF TJE INVENTION having relatively high natural vibration, along the feeder line of rail state. This method raises problems such as the deposition of the conductor by frictional heat, the deposition of the conductors to each other, or the wear of the conductor, etc. It is proposed in order to avoid the problems caused by the above friction to mount the current composed of the above conductors on a rotatable rigid body at the conductive center to form a roller current collector and to collect an electric current from the feeder line while rotating the collector in synchronization with the vehicle movement. However, such a roller current collector receives a great deal of shocking force due to the centrifugal force at high speed and damage occurs due to the conductors contact with the feeder line, the wear of the conductors due to the partial friction of the conductors with the feeder line and the friction of the conductors to each other, and the deposition of the conductors to each other. Further to adopt a synchronous rotation, the current collector becomes complicated and heavy.

SUMMARY OF THE INVENTION

This invention contemplates eliminating the various disadvantages of the conventional current collecting roller and to provide a novel and improved current collecting roller.

The feature of the current collecting roller of this invention resides in the provision of the roller which comprises a composite current collecting element having liquid elastomer completely filled in between plural flexible planar or linear conductors, wherein at least one end of the conductors is exposed at a cylindrical current collecting surface contacting with a feeder line or current collecting line of a rigid conductor, and a support having a rotary shaft electrically or mechanically contacted or connected between the conductors in the composite current collecting element.

The current collecting roller of this invention has the following various advantages:

1. Since the current collecting roller using a liquid elastomer such as, polyurethane rubber acts like a solid tire, the current collecting roller may rotate only by pushing it onto the feeder line.
- 5 2. Since the respective conductors are surrounded by elastomer, the bending deformation or vibration of the conductors themselves are restrained. Particularly, the shocking force acting on the conductor when contacting the feeder line is almost negligible. For this reason, 10 the damage of the conductor, or the deleterious effect of the interference between the conductors is eliminated so as to greatly improve the durability. Generally, since the liquid elastomer material used for the current collecting roller has relatively large attenuating 15 coefficient, it acts as a vibration-absorbing material, and the damage to the conductor is prevented.
3. Even though the feeder line has geometrical irregularities when the current collecting roller rotates in contact with the rigid conductor rail, feeder line or current collecting line to collect the current, proper spring action of the elastomer between the flexible conductors and the rigid conductor rail prevents the current collecting roller from jumping up, and even if it jumps up, 20 an electric contact is held with the feeder line by the returning force of the flexed conductor and the elastomer. Thus, current collection at high speed can be accomplished.
- 25 4. Since the friction coefficient between the current collecting roller and the feeder line can be increased by using a proper liquid elastomer, the slip between the current collecting roller and the feeder line may be almost negligible. For this reason, the friction of the elastomer or conductor on the surface of the current roller may be greatly reduced.
- 30 5. When electricity is applied to a vehicle using the current collecting roller of this invention, the electricity is applied to the flexible conductor exposed on a current collecting surface of cylindrical shape contacting the feeder line. Another current collector is used at the end surface of a rotary shaft of the current collecting roller for feeding the electricity to the vehicle.

BRIEF DESCRIPTION OF THE DRAWINGS

The other objects, features and advantages of the present invention will become apparent from the following description taken in conjunction with the accompanying drawings, in which,

FIG. 1 is a perspective view of a composite current collecting element of one embodiment of the present invention;

FIG. 2 is a partial sectional view of one embodiment of the current collecting roller of this invention;

FIG. 3 is a longitudinal sectional view of the current collecting roller shown in FIG. 2;

FIG. 4 is a plan view of another embodiment of the current collecting roller of the present invention;

FIG. 5 is a partial sectional view of a further embodiment of the current collecting roller of this invention;

FIG. 6 is a view similar to FIG. 5, but showing still another embodiment of the roller;

FIG. 7 is a partial sectional view of still another embodiment of the current collecting roller of this invention;

FIGS. 8A and 8B, and 9A and 9B are views of partial structures of the embodiments of the current collecting roller of this invention;

FIG. 10 is a sectional view of still another embodiment

ment of the current collecting roller of this invention;

FIGS. 11 to 15 are views of still another embodiment of the current collecting roller using a ring or rod for fixing the resilient conductors;

FIGS. 16 to 20 are views of still another embodiment of the current collecting roller utilizing a belt implanted with plural resilient conductors;

FIGS. 21 and 22 are views of still another embodiment of the current collecting roller of this invention;

FIGS. 23 and 28 are views of a metal foil conductor and a spacer used in the current collecting roller of this invention;

FIG. 29 is a perspective view of still another embodiment of the current collecting roller using a metal foil conductor and spacer in an assembly shown in FIG. 23;

FIG. 30 is a partial perspective view of still another embodiment of the current collecting roller using a ring to mount a metal foil and spacer to a conductive supporting rigid body of this invention;

FIG. 31 is a partial perspective view of the roller using the metal foil and the spacers as shown in FIG. 27;

FIG. 32 is a view of the metal foil and the spacer of another embodiment and of their assembly of the roller of this invention;

FIGS. 33 to 40 are views of other embodiments of the metal foil and the spacer used in the roller of this invention;

FIG. 41 is a perspective view of the current collecting roller in still another embodiment using the foil of this invention;

FIG. 42 is a partial side view of the roller shown in FIG. 41;

FIGS. 43A to 47B are views of the embodiment of the conductive metal foil used in the roller of this invention;

FIGS. 48 to 57 are views of various embodiments of the current collecting roller using a gauze;

FIG. 58 is a view of an embodiment of a composite current collecting element using two sheets of reinforcing circular plates;

FIG. 59 is a view of the embodiment of the composite current collecting roller using three elements;

FIGS. 60 to 63 are partial sectional views of the current collecting roller showing the density of the lead wires and their graphical representations for the explanatory purpose; and portions

FIG. 64 is a view of one embodiment of the transportation apparatus incorporating the present invention.

DETAILED DESCRIPTION OF THE PREFERRED EMBODIMENTS

Reference is now made to the drawings, particularly to FIGS. 1 to 10, which show a current collecting roller which comprises resilient lead wires including contacting portions and an electroconductive disc having holes provided near the peripheral edge thereof for connection electrically and mechanically to the resilient lead wires. Constant lengths of resilient lead wire bundles are inserted through the holes in such a manner that both the ends of the bundles are directed outwardly in a U shape. A plurality of discs are superimposed and held together and a liquid elastomer is caused to flow between the lead wires to form an integral structure with the discs.

In FIG. 1, reference numeral 1 represents an electroconductive disc made of metal such as high tensile

strength aluminum alloy having a plurality of holes 2 provided equidistantly near the peripheral edge thereof. Numeral 3 is resilient lead wire bundles formed, for example, of 100 to 300 of steel wires, to be inserted through one hole 2 such that both ends 4 and 5 thereof are bent outwardly to form a U shape. Instead of bending the lead wire bundle after the bundle is inserted through the hole, the bundle may be bent in advance in the U shape and then inserted through the hole. The resilient lead wires may be any of aluminum, aluminum alloy wire, copper, copper alloy wire stainless steel wire, or steel wire.

FIG. 2 shows a partial sectional view of one embodiment of the current collecting roller of this invention, 15 and FIG. 3 shows a sectional view of the roller shown in FIG. 2. In FIG. 2, the lead wire bundles 3 are inserted radially through the respective holes 2 of two thin plate discs 1 and 1' and these two discs are superimposed. Then, push plates 6 and 7 are placed on both sides of 20 the discs, and these are tightened by bolt 11 and nut 12 to a support body 10 composed of two portions 8 and 9. Numerals 13 and 14 are rotary shafts of the support body 10, 15 are bearings of the rotary shafts, 17 are bearing nuts, and 18 are bearing washers. Elastomer 25 19, such as polyurethane, is solidified upon filling between the steel wire bundles 3 and the disc 1 and 1' and outside thereof. Elastomer 20 also fills the holes provided near the periphery of the push plates 6 and 7. 16 30 is a cylindrical current collecting surface with lead wire ends 21 exposed on the surface of the cylindrical current collecting surface 16. In FIG. 1, the composite current collecting element is formed with the liquid elastomer 19 filled between the discs 1 and 1', push plates 6 and 7, lead wire bundles 3 and therebetween and then solidified to form an integral structure.

The operation of the push plates 6 and 7 shown in FIGS. 2 and 3 require consideration of the following three points. First, to prevent the resilient lead wire bundles 3 from greatly expanding, it is necessary to 40 push the lead bundles 3 to the discs 1 and 1' with high pressure so that even if the elastomer 19 is poured, the electroconductivity between the lead bundles 3 and the discs 1 and 1' may not be damaged. Second, a reinforcing effect against the centrifugal force is required. This 45 is normally difficult with the elastomer 19 and the discs 1 and 1' or push plates 6 and 7. For this reason, the holes 20 are formed with proper diameter and position in the push plates 6 and 7, and the elastomer 19 occupies these holes 20 so as to perform the reinforcing effect. In order to obtain a similar effect, the holes 20 50 may be formed in the discs. Third, it is necessary to quickly release the heat produced by the current through the lead wire bundles or the heat produced by the elastomer pushed onto the rail toward the shaft.

As shown in FIG. 3, instead of the resilient lead wire bundles 3 disposed radially, they may be disposed at a 55 constant angle and oblique direction with respect to the radial direction as shown in FIG. 4. In FIG. 4, numeral 1 represents a disc, 3 lead wire bundles, and 26 wires for holding the lead wire bundles at a proper angle. The bundles are interleaved between the push plates 6 and the disc 1 or the disc 1 and the disc 1'. Holes are formed at proper positions of the disc for receiving tightening bolts and the bundles are tightened there-through. After the angle of the lead wire bundles is determined and fixed with the bolts, the bolts may be left 60 as is or removed.

FIG. 5 shows the structure of many discs 1 superimposed for collecting a great deal of current. In order to pass the lead wire bundles 3, when many discs 1 are superimposed with holes 2 at the peripheral edge thereof, as shown in FIGS. 2 and 3, or as shown in FIG. 5, the discs 1 may be superimposed in such a manner that the holes 2 are displaced by one half of the pitch of the holes 2 with respect to each other, or the discs and the push plates are superimposed alternatively. The respective positions of the discs may be displaced by the angle divided by the number of the discs superimposed at an angle of pitch of the hole through which the lead wire bundles are inserted so that the density of the lead wires are as uniform as possible on the circular peripheral surface of the discs.

A plurality of discs 1, with the lead wire bundles 3 through the holes 2 of the peripheral edges thereof, are tightened with the bolts 11 and the nuts 12 between the push plates 6 and 7 and the electroconductive support body 22. The elastomer 19 is then poured therebetween. Numeral 23 represents the bearings and 24 is a rotary shaft of the support body 22. A number of holes 20 for facilitating the pouring of the elastomer may be provided at proper positions in the push plates and the discs.

The electroconductivity between the lead wire bundles and the discs is normally obtained by pushing the bundles onto the discs and the push plates. If, however, the material has relatively small Young's modulus as the lead wires and has plastic properties such as, aluminum, the electroconductivity between the lead wire bundles and the discs may sometimes be decreased by the flow of the liquid elastomer. In such a case, an electric connection between the lead wire bundles and the discs may be improved by soldering, welding or a mechanical process after the lead wire bundles are passed through the holes on the discs.

FIG. 6 shows the roller having peripheral grooves 25 on the circular periphery of the roller shown in FIG. 5, wherein the same numerals and characters show the same parts as these therebetween.

There may be one or several grooves 25 as shown in FIG. 6. The grooves 25 dissipate heat. This is the required heat dissipating effect for dissipating the heat generated by the current flowing through the lead wire bundles 3, or the heat produced by the deformation of the elastomer 19.

A uniform contacting pressure between the roller and the feeder line of rail shape should be maintained. In order to increase the current capacity, the width of the roller must be enlarged, but a broad roller introduces irregular contacting pressure, and accordingly, it becomes difficult to maintain uniform contact between the lead wires and the rail. By the provision of the groove 25, the roller divided by the grooves may act as independent rollers with respect to the rail so as to maintain uniform contacting pressure. The grooves 25 may not only be circular peripheral, but may be like the tread surface of a tire of a vehicle.

FIG. 7 shows partial sectional view of a further embodiment of the present invention. Numeral 3 represents lead wire bundles, 27 to 33 are electroconductive discs having holes 2 for inserting the lead wire bundles at the periphery thereof, and 34 and 35 are push plates. Bolts 36 at push plates 34 and 35 tighten the superimposed discs 27 to 33 with the lead wire bundles inserted therein. The bolts 37 and nuts 38 are for fixing the elec-

troconductive discs 27 to 33 and the push plates 34 and 35 to the supports 39 and 40 opposite to each other, and rotary shafts 41 and 42 are provided thereat. 43 and 44 are bearings. 45 shows the end surface of the lead wires exposed at the outer peripheral surface of the roller. 25 are grooves provided on the periphery of the roller. The discs have holes formed at the periphery thereof for inserting the lead wire bundles therethrough. The holes in each disc are slightly displaced with respect to the holes in a superimposed disc. The holes 45 shown in FIG. 7 are not for passing the lead wire bundles, but are provided for the flow of the liquid elastomer 19. The holes 20 provided at the push plates 34 and 35 are provided for the same purpose as that of 15 those holes 20 shown in FIG. 3. Numeral 19 is the elastomer. 46 and 47 are partially bent at the peripheral portion of the push plates so the line density of the lead wires is uniform. Numeral 48 is the part bent at the outer periphery of the disc 30 for the same purpose. In 20 FIG. 7, the diameters of the discs 30 or push plates 34 and 35, when bent, are larger than those of the other discs 27 to 33, but the same diameter of the discs may be bent similarly.

FIGS. 8 and 9 are explanatory views showing the effect of bending at the outer periphery of the push plates or discs, wherein FIG. 8 is prior to bending, while FIG. 9A shows a side view 9B shows front view after bending.

Numeral 49 represents an electroconductive disc, 50 push plates or electroconductive discs, and 16 the cylindrical current surface of the current collecting roller. As shown in FIGS. 2 or 8, when the adjacent disc near the outer periphery of the disc or push plates (part to which the lead wire bundles are pushed) are in parallel, or as shown in FIGS. 5 and 6, when they are expanded as going to the outer periphery, even if the discs or push plates are superimposed, and pushed, the lead wire bundles do not expand in circular peripheral direction of the roller (see FIG. 8B). On the contrary, as shown by 51 and 52 in FIG. 9A, if the distance between the adjacent discs or the discs and the push plates is decreased gradually toward the outer periphery thereof by bending the discs or push plates, the lead wire bundles are expanded in a sector shape in peripheral direction of the current collecting roller as shown by A-A in FIG. 9B. For this reason, the current collecting roller may have small irregularity of the density of the lead wire in peripheral direction at the cylindrical current collecting surface of the roller. A small irregularity of the density of the lead wire means that the current capacity is irregular at the respective parts of the circular periphery of the current collecting roller.

FIG. 10 shows partial sectional view of the embodiment of the effect shown in FIG. 9. Numerals 53 and 54 represent push plates, and 55 and 56 are discs having holes 2 for inserting the lead wire bundles. 58 is a rivet for fixing these.

As shown in FIGS. 1 through 10, the current collecting roller which comprises resilient lead wire bundles of U shape are inserted through holes near the peripheral edge of the disc. A plurality of these discs are superimposed and tightened. A liquid elastomer is placed between the lead wire bundles and the discs and their periphery, and is then solidified. The structure, therefore, does not destroy itself, due to the centrifugal force of the rotation thereof, and is extremely rigid mechanically. The electric connection between the discs and

the lead wires is very good, and yet contact is always maintained between the current collecting roller and the current collecting wires or feeder lines during rotation, by the resiliency of the elastomer and the lead wires.

FIGS. 11 to 15 show the embodiments of the current collecting rollers using a ring or rod for fixing the resilient lead wires. More particularly, it is a current collecting roller which comprises an electroconductive ring or electroconductive rod, a plurality of relatively constant length of resilient lead wires of U shape closely arranged to the ring or rod in such a manner that both ends thereof are directed outwardly. A plurality of current collecting rings or rods are supported on a rotary shaft support, and liquid elastomer is placed between the lead wires, and current collecting rings or rods to form an integral solid structure.

FIG. 11 shows a perspective view of the current collecting element. Numeral 59 represents a metal ring such as steel and 60 is a constant length of resilient lead wires which are bent in a U shape. Both ends 61 and 62 of the lead wires are directed outwardly to be engaged with the ring, and similarly many lead wires are arranged closely around the ring to form a current collecting ring 63.

FIG. 12 shows superimposed current collecting rings 63, 64, 65 and 66 so arranged on the horizontal or slightly tapered peripheral surface of rotary support 67 held by the push plate 68. Liquid elastomer 19 is filled between the lead wires and the current collecting ring to be integrally solidified. Numeral 69 represents a rotary shaft. Similar to the embodiment shown in FIG. 1, the bearings are provided on the rotary shaft, but are not shown. 16 is the cylindrical current collecting surface of the current collecting roller.

FIG. 13 shows still another embodiment for supporting the current collecting ring, wherein FIG. 13A is a partial sectional view, and FIG. 13B is a plan of FIG. 13A.

The current collecting rings 63 and 64 are arranged between the comb shaped flange 71 of rotary support 70, and the supporting ring 72. The support 70 and the support ring 72 are fixed with bolts 73. A liquid elastomer such as urethane is filled between the lead wires and the current collecting ring and solidified to form a solid integral structure. In order to further strengthen the lead wires, the lead wires are inserted into a metal foil conductor having holes for inserting the lead wires, and the foil conductor may be fixed to the support. In this case, the sectional configuration of the electroconductive ring may be a circle, rectangle, etc.

FIGS. 14 and 15 show the current collecting roller utilizing an electroconductive rod, wherein FIG. 14 is a front sectional view and FIG. 15 is a side view thereof.

Numeral 74 represents a rotating electroconductive support and 75 is the side thereof. 76 is an electroconductive rod arranged to be fixed uniformly near the side peripheral edge thereof and 77 is a resilient lead wire bundle of a U shape of constant length engaged at both ends thereof and directed outwardly. 78 is an electroconductive pressing ring having holes 79 near the peripheral edge thereof. 80 is the engaging portion of the pressing ring engaged or welded with the engaging grooves 81 of a part of the electroconductive support 74. 19 is a liquid elastomer such as urethane filled and solidified between the lead wires.

In the current collecting roller utilizing the ring or rod shown in FIGS. 11 to 15, the resilient lead wires may be arranged at a constant angle or oblique direction with respect to the radial direction as shown in FIG. 4. The current collecting roller utilizing the ring or rod shown in FIGS. 11 to 15 is adapted for use when a current collecting roller having relatively large linear density is manufactured, that is one having many lead wires. Since the lead wires are engaged with the ring or rod, it is very strong against the centrifugal force and thus prevents the throwing of the lead wires. In FIG. 12, the composite current collecting element is filled with the elastomer 19 between the lead wires 60 and the rings 63, 64, 65 and 66 and therebetween.

FIGS. 16 to 20 show a current collecting roller utilizing the belt implanted with many resilient lead wires. More particularly, a current collecting roller which comprises a resilient support secured around the electroconductive central portion with an electroconductive cylinder secured thereonto. A belt implanted with many resilient lead wires is wound thereon and secured onto the resilient cylinder, and liquid elastomer is placed between the lead wires provided on the belt and then solidified. The resilient support may be omitted, and the electroconductive cylinder may be omitted, or instead of the cylinder, the belt with an electroconductive tape adhered (metal tape or metal foil conductor, etc.) to the back thereof may be used. In this case, the member adhered at the back is used instead of the electroconductive cylinder.

FIG. 16 shows a sectional view of the belt implanted closely with many lead wires. Numeral 82 represents the lead wires, 83 a rubber-fiber laminated cloth, and 84 an electroconductive backing material such as, metal net, electroconductive rubber, metal foil conductor, etc. However, this backing material may be omitted.

FIG. 17 shows the embodiment of the current collecting roller utilizing the belt without the resilient support. Numeral 85 represents an electroconductive rigid central support and 86 is a tightening wire such as steel wire tensioned in peripheral direction so that the belt will not fly out due to the centrifugal force on the rubber-fiber laminated cloth 83 of the belt. 87 are holes provided at the electroconductive rigid support 85, through which tightening wires 86 are mounted to the flange portion 89 of the electroconductive rigid support by a proper method such as screws 88. Numeral 90 is an adhesive agent in the holes 87 for assuring the securing of tightening wire 86. Numeral 91 is the journal of the rigid support. Bearings 92 and a keep ring 93 are fixed to the rigid support 85 by fixing fittings 94. 16 is a cylindrical current collecting surface with lead wire ends 21 exposed on the current collecting surface.

FIG. 18 shows the embodiment of the tightening wire 86. Both ends of one tightening wire 86 are inserted through two holes 87 provided at the electroconductive rigid support 85 to be fixed by the screws 88 or to the flange 89. The tightening wire 86 is preferably wound in a superimposed manner of proper length. If the tightening wire 86 is fixed with an adhesive in the holes 87 so that the belt 83, the backing material 84 and the electroconductive rigid support 85 are secured by the electroconductive adhesive, its characteristics become even better.

Thus, the belt implanted closely with the lead wires is secured to the rigid electroconductive support using

the tightening wire, and thereafter liquid elastomer 19 is placed between the lead wires and solidified to form an integral structure. The trimming 95 provided of the elastomer 19 is provided on the rail surface during contact of the roller with the rail to assure contact of the lead wires 82.

As shown in FIG. 19, the elastomer 19 may be cut at both side ends. Though the embodiment shown in FIG. 17 fixes the belt and the electroconductive rigid central support using the tightening wires 86, the tightening wires 86 may be omitted and the belt affixed to the electroconductive rigid central support 85 with an adhesive agent in the event that sufficient adhering between the belt and the electroconductive rigid central support 85 is obtained, or if the centrifugal force is not large at high speed. At this time, it may freely use the electroconductive adhesive, or backing material 84. As shown in FIGS. 17 and 19, the grooves 96 provided on the electroconductive rigid central support 85 may be extended to 97, with projections 98 provided on the rigid central support 85 or keep ring 93, as shown. As shown in FIG. 17, the spring constant of the current collecting roller is considerably hard, but in some cases, a current collecting roller having a softer spring constant may be required. For this reason, the resilient support may be provided between the belt and the electroconductive rigid central support.

FIG. 20 shows the embodiment of the above case. Numeral 99 represents an electroconductive rigid central support, 100 a resilient support composed of resilient rubber, etc., 101 a resilient cylinder made of electroconductive metal secured to the resilient support 100 and 102 a resilient lead wire belt electrically connected in contact with the resilient cylinder 101 as shown in FIG. 16. Elastomer 19, such as urethane, is placed between many resilient lead wires 103 closely implanted on the belt and then solidified. 104 is a flexible lead wire for electrically connecting the electroconductive resilient cylinder 102, which may pass through the resilient support 100, or may be connected at the exterior of the resilient support 100. Further, the resilient support 100 may be an insulating elastomer, or electroconductive elastomer. As shown in FIGS. 17 and 18, in order to fix the belt, a flexible tightening wire such as steel cord may be used, or a resilient cylinder may be used as the backing material. The securing of the belt to the resilient support or electroconductive rigid central support may be conducted using the tightening wire, or adhering, or other method.

The features of the current collecting roller using the belt shown in FIGS. 16 to 20 with respect to the other system of the current collecting roller is such that the linear density thereof may be relatively constant. For this reason, a product having less irregularity of characteristics may be produced.

As the foregoing description, the current collecting roller shown in FIGS. 1 to 20 uses flexible lead wires, shown as straight lead wires in the drawings. The wires need not always be straight, but as described below, they may be in a coil or wave or twisted. In order to enlarge the current capacity of the current collecting roller, lead wires having a large diameter are used, or the density of the lead wires may be enlarged, or both. However, it hardens the spring characteristics to use the lead wires having large diameter, or to enlarge the density of the lead wires. If the spring characteristics are hardened, the contacting area of the current col-

lecting roller and the current collecting line or the feeder line becomes small, and accordingly the contact of the current collecting roller with the current collecting line cannot be maintained at high speed because of the differential geometrical irregularity of the current collecting wire. And, since the contacting area is reduced, the current capacity is not improved.

In order to eliminate this disadvantage, it is important that the spring characteristics do not become so hard even though lead wires having a large diameter are used in large numbers. For this reason, if the non-linear lead wires or twisted wires having larger flexibility are used, preferable characteristics may be obtained.

In the drawing, numeral 105 represents electroconductive rotary rigid central supports and 106 non-straight resilient lead wires secured to the peripheral surface thereof. The lead wires are in a zig-zag fashion as shown in FIG. 21 or as a spiral coil 107 as shown in FIG. 22. The liquid elastomer 19 is placed between the lead wires 106 and 107 and then solidified.

As shown by 108 in FIG. 22, the lead wires may be partially bent. Such partially bent wires are convenient for producing the current collecting roller using the belt shown in FIGS. 16 to 21.

The foregoing description relates to the current collecting roller using the lead wires, however, the current collecting roller may use metal foil conductors rather than lead wires. The metal foil conductor having contractions, projections, holes or holes with slits, and electroconductive or insulating spacer foil having similar contractions, projections, holes, etc. are alternatively arranged every other sheet. A metal foil conductor having projections, wavy and bellows spacing action or spring action is arranged to the metal foil conductor having the contraction to be fixed around the electroconductive rigid support by utilizing the engaging rigidity, projections, holes, etc., and thereafter liquid elastomer is placed between the metal foil conductors, or between the metal foil conductor and the spacer in a lamination and then solidified to form an integral structure with the electroconductive rigid support as the current collecting roller of the transportation apparatus.

Referring to the drawings, particularly to FIGS. 23 to 27, wherein FIGS. 23A to 27A show metal foil conductors in such a manner that the upper contacting portions are of comb shape, while the lower contacting portions are continuous, while FIGS. 23B to 27B and 25C to 27C show electroconductive or insulating spacer foil similar to the lower portion of the metal foil conductor.

In FIG. 23A, numeral 109 represents metal foil conductor of comb shape at the upper contacting portion with a continuous contraction 110 at the middle thereof. The aforesaid metal foil conductor 109 shown in FIG. 23B has the same shape as the spacer at the lower portion of the metal foil conductor for use with the metal foil conductor 109.

FIG. 24A shows metal foil conductor 113 having a continuous portion cut out to the center from one side. FIG. 24B shows the spacer 114 of the same shape as that of the lower portion thereof, for use with the metal foil conductor 113. FIG. 25A shows metal foil conductor 117 having an upward slit 115 and holes 116 communicated therewith at the lower portion thereof, and FIGS. 25B shows the spacer 120 of the same shape as the lower portion of the metal foil conductor, and FIG. 25C shows the spacer 120 having cutout 121 of the di-

diameter of the hole 116. FIG. 26 shows metal foil conductor 122 having holes 123 at the lower portion thereof, using the spacer 124 and 125 similar to those shown in FIGS. 25C and 24B. The metal foil conductor 126 shown in FIG. 27 has two cutouts 127 at the inside thereof. The spacer 128 is provided with a similar cutout 130 while spacer 129 has no cutout. Various metal foil conductors shown in FIGS. 23 to 27 and the spacers corresponding thereto are alternatively arranged.

FIGS. 28A to 28D show the roller in which metal foil conductors and spacers are alternately arranged and laminated in a partial side view, wherein the same numerals represent the same parts. Numeral 131 represents metal foil conductors, 132 spacers and 133 an electroconductive rigid support. As shown in FIG. 28A, the metal foil conductor 131 may be arranged vertically in the radial direction of the electroconductive rigid support 133. The upper portion of the conductors may be bent as shown in FIG. 28B or further as shown in FIG. 28C, may be arranged at an angle in radial direction together with the spacers 132. As shown in FIGS. 28B and 28C, the metal foil conductors 131 are arranged obliquely with respect to the radial direction of the rigid support 133 so as to soften the spring characteristics and increase the contacting area with the rail, and thus increasing the current capacity.

The spacers exemplified in FIGS. 23 to 27 are not limited only to the electroconductive material, but may be of insulating material, and the thickness may be proper for the arrangement on the periphery of the electroconductive rigid support with a predetermined number of metal foil conductors, and may be provided the a taper. Further, as shown in FIG. 28D, the spacer 132 may be of the same height as that contraction the metal foil conductor 131. the

FIG. 29 shows a perspective view of the current collecting roller assembled with the metal foil conductor and spacer shown in FIG. 23. Numeral 134 represents an electroconductive rigid support and 135 a metal foil conductor. There is provided a rotary shaft 137 for mounting the bearings through flanges 136 at the electroconductive rigid support 134. The rigid support 134 has peripheral grooves 141 having projections 140 engaged with the continuous contractions 139 of the metal foil conductors 135 and the spacer 138. The metal foil conductors 135 and the spacers 138 are arranged alternatively in relatively close contact with each other and a side cover 143, having projections 142 engaged with the cutouts 139, is held by the screws 144 to the rigid support 134. Liquid elastomer 19, such as polyurethane, is placed in the laminated portion of the metal foil conductors 135 and the spacers 138, and solidified to form an integral structure of the metal foil conductors, spacers and rigid support. Numeral 16 is the cylindrical current collecting surface of the current collecting roller.

FIG. 30 shows a perspective view of the current collecting roller mounted on an electroconductive rigid support with the metal foil conductor and the spacer using a ring. Numeral 145 represents a metal ring having great strength, small specific weight, and a relatively large Young's modulus. 146 are metal foil conductors and 150 are spacers. A rotary shaft 149 is provided for mounting the bearings through flanges 138 on the electroconductive rigid support 147. In the roller shown in FIG. 30, metal foil conductors 113 and the spacers 114 shown in FIGS. 24A and 24B are used. The

metal foil conductors 117 or spacers 120 shown in FIGS. 25A, 25B and 25C may also be used. In this case, in order to insert the metal foil conductor 117 on the ring 145, slits 115 and holes 116 are utilized, or they 5 may be easily inserted by twisting the metal foil conductor 117. In order to tightly insert the metal foil conductors and the spacers, it becomes difficult to insert the last few spacers shown in FIG. 25. Therefore, the spacer shown in FIG. 25C may be inserted from upper 10 portion of the ring (outer peripheral direction), or the spacer exemplified in FIG. 26C may be inserted from side. The metal foil conductors may be inserted on a predetermined number of rings 145 first, or the metal foil conductors 117 shown in FIG. 25A and the metal 15 foil conductors 113 shown in FIG. 24A may be used. If the metal foil conductor 122 shown in FIG. 26 is used, a predetermined number of metal foil conductors 122 are passed through the bar corresponding to the holes 123 of the metal foil conductors 122 first, the bar 20 is cut at proper length, and both ends of the bar are welded. The spacers shown in FIGS. 26B and 26C are inserted therethrough on the ring 145. After the spacers and metal foil conductors shown in FIGS. 24 to 26 25 are assembled as shown in FIG. 30, the side cover 151 is fixed with screws 152, and then liquid elastomer 19 is placed in the laminated portion of the metal foil conductors 146 and the spacers 150 and solidified to form an integral structure.

FIG. 31 shows a partial perspective view of the roller 30 using metal foil conductors 126, spacers 128 and 129 shown in FIG. 27. Numeral 153 represents an electroconductive rigid support. Projections 154, provided on the periphery of the rigid support, engage the cutouts of the metal foil conductors 155 (FIG. 27A) and spacers (FIG. 27B) arranged on the circular periphery of the rigid support 153. As aforementioned, since the metal foil conductors 155 and the spacers are very thin, they may be easily inserted. The spacers 129 shown in FIGS. 27C are preferably used at the last part of the insertion. After a predetermined number of metal foil conductors and the spacers are thus inserted into the projections 154, the side covers 157 are fixed to the rigid support 153 by the screws 158 from both sides of the rigid support 153. Then the liquid elastomer is placed therein and solidified. The side cover 151 shown in FIG. 30 or the side cover 157 shown in FIG. 31 may be omitted to save weight in the roller. If the side covers are eliminated, a mold may be used for the liquid elastomer.

As an alternative, the projections may be on the metal foil conductor and the spacer, and the engaging cutouts may be on the electroconductive rigid support. FIG. 32A shows metal foil conductor 159 provided with projections 160. FIG. 32B shows spacer 161 provided with the same projections 162. FIG. 32C shows partial view of the assembly of the metal foil conductor 159 and the spacer 161.

Numeral 166 represents an electroconductive rigid support and 163 an engaging cutout provided on the rigid support. After the metal foil conductors 159 and the spacers 161 are arranged alternately, a side cover 164 is mounted on the rigid support 166 with screws 165, and the metal foil conductor 159 and the spacer 161 are fixed. Then, a liquid elastomer is placed in the structure and solidified to form an integral structure of the laminated portion of the metal plates 159, the spacers 161, the rigid support 166 and the side cover 164.

For the purpose of facilitating the flow of liquid elastomer, softening the spring characteristics, or lessening the weight, grooves, projections, waves, bellows, cutouts, etc. may be provided on one or both sides of the spacer independently or longitudinal or lateral or both of the plural spacers. FIGS. 33 to 38 show the examples of the above cases. FIG. 33A shows a front view and FIG. 33B shows a side view, with a step 167 in lateral direction. FIG. 34A is a front view, and FIG. 34B shows a side view showing wave 168. FIG. 35A is a front view, and FIG. 35B is an elevational view showing grooves 169. FIG. 36A is a front view and FIG. 36B shows a side view showing projections 170 in the thin plate. FIG. 27A is a front view and FIG. 37B is an elevational view showing waves 171. FIG. 38A is a front view and FIG. 38B is a side view showing a curl 172.

With the conductors shown in FIGS. 33-38, the spacers may be omitted by providing independent or plural projections, waves, curls, etc. at proper locations and distances on the lower half part of the electroconductive metal foil conductor. If an electroconductive metal foil conductor having such projections, waves, or curls is used, the spacer may not only be omitted, but the side cover may also be omitted by utilizing the projections, waves, etc. for spring action, thus offering significant advantages in working and assembling.

FIGS. 39 and 40 show a metal foil conductor provided with projections. FIG. 41 is a perspective view of the current collecting roller using such foils and FIG. 42 is a partial side view thereof. In the metal foil conductor using the aforesaid projections, waves, curls, etc., two types of metal foil conductors having projections, waves, curls, etc. are provided at different positions alternately arranged. This will now be described in detail with reference to the drawings. FIG. 39 shows the electroconductive metal foil conductor 174 provided with three projections 173, and FIG. 40 shows the metal foil conductor 175 with two projections 176. The conductors are provided with engaging cutouts, projections, holes, or holes with slits for fixing to an electroconductive rigid support as above. The metal foil conductors shown in FIGS. 39 and 40 have engaging cutout 177. The two types of metal foil conductors 174 and 175 are alternately arranged as in the roller shown in FIG. 41. FIG. 42 shows a partial sectional view thereof wherein metal foil conductors are arranged. In FIG. 41, numeral 178 represents an electroconductive rigid support, 179 an engaging projection and 182 peripheral grooves composed of two projections. 180 are flanges, and 181 is a rotary shaft for mounting the bearings. The assembling is conducted by the following steps:

Two types of metal foil conductors 174 and 175 are inserted alternately into the peripheral grooves 182. At inserting, if the metal foil conductor is inclined obliquely with respect to circular peripheral direction of the electroconductive rigid support 178, it may be easily inserted. The last several metal foil conductors may not, however, be inserted by this method, but may be inserted by the following steps: The projections 173 and 176 are provided on the metal foil conductors 174 and 175. The metal foil conductors already inserted into the peripheral grooves 182 are compressed by the spring action of the projections, and considerable space is thereby provided for inserting the last several metal foil conductors by the normal method. Then the compression force applied to the metal foil conductors pre-

viously inserted is removed whereby the metal foil conductors are uniformly arranged on the circular periphery of the peripheral groove 182 of the electroconductive rigid support 178. Liquid elastomer 19 is then placed into the laminated portion of the metal foil conductors and solidified to form an integrated structure.

FIG. 43A shows a front view and FIG. 43B shows a side view of another conductor configuration. A bent portion 183 is provided at the lower half portion as the electroconductive metal foil conductor 186 having the engaging holes 184 and slits 185. In this case, as above, the conductors are arranged to form the roller.

FIG. 44 and 45 show one set of electroconductive metal foil conductors 190 and 191 alternately arranged. FIG. 44A is a front view thereof, while FIG. 44B is a side view thereof. FIG. 45A is a front view, while FIG. 45B is an elevational view thereof, and FIG. 45C is a perspective view thereof.

Numeral 187 represents waves and 188 represents engaging projections with the rigid support. The wave 187 is provided laterally in case of the metal foil conductor 190. The wave 189 is provided longitudinally in case of the metal foil conductor 191, and the projections 188 are similar to that of the metal foil conductor 190.

FIGS. 46 and 47 show one set of metal foil conductors 193 and 194. Two projections 192 are provided in the metal foil conductor 193, and one projection 195 is provided in the metal foil conductor 194, and these two types of metal foil conductors are alternately arranged.

The detailed shapes of the projections, waves, etc. provided at the metal foil conductors for eliminating the spacers shown in FIGS. 39 to 47 are determined to be arranged generally at uniform distances when these metal foil conductors are fixed to the electroconductive rigid support.

In the current collecting roller using the metal foil conductors shown in FIGS. 23 to 47, liquid elastomer is allowed to flow so as to be displaced slightly from both side surfaces of the metal foil conductors or spacers so that it is easily solidified.

The current collecting roller using the metal foil conductors shown in FIGS. 23 to 47 are not well suited for collecting an electric current at high speed because of the effect of centrifugal force on the structure thereof. However, it permits the flow of a relatively large current in comparison with the current collecting roller utilizing the linear conductor, and thus may be used when a large current is required.

FIGS. 48 to 57 show various examples of the current collecting rollers using gauze. More particularly, they show a current collecting roller which comprises a plurality of gauzes made of lead wires (hereinafter called gauzes) superimposed after a predetermined shift. Keep plates tightening both surfaces of the gauzes and a liquid elastomer is placed between the gauzes or between the keep plates and the gauzes and then is solidified. The composite current collecting element may also be made by cutting or grinding the composite material of the gauzes and solidified elastomer to a predetermined size and shape, the liquid elastomer having been poured into the superimposed gauzes under pressure. A support member (rotary support material) having a rotary shaft is electrically and mechanically connected therewith.

FIG. 48 shows the gauze punched in a coaxial circle and FIG. 49 shows the current collecting roller made with several gauzes superimposed. Numerals 197 and 198 are keep plates comprising a thin plate of electro-conductive material such as a high tensile strength aluminum alloy plate. The gauzes are superimposed between the keep plates 197 and 198, and the keep plates 197 and 198 are tightened on the circular periphery with rivets 199 and 200. Numerals 201 and 202 are support bodies for fixing the keep plates 197 and 198 using bolts and nuts 203 and 204. 205 and 206 are rotary shafts of the support body, and 206 and 207 are bearings. Rivets 199 and 200 are used to tighten the gauzes, but bolts may be used, or thin plate working of the keep plates 197 and 198 may also be utilized, or the mold into which liquid elastomer flows may also be used. In the embodiment shown in FIG. 49, the gauzes are fixed from both sides by the keep plates, and the liquid elastomer 19 such as polyurethane flows therebetween and is solidified to form an integral current collecting roller.

FIGS. 50 to 52 show still another embodiment of the present invention. FIGS. 50 and 51 are explanatory views for FIG. 52. FIG. 50 shows the roller formed by superimposing several gauzes 209. A plate is pressed to function as the keep plates 210 and 211 in such a manner that a predetermined number of gauzes 209 are inserted and the final pressing of the thin plate tightens the gauzes. The pressing expands the gauzes into a sector shape (see FIG. 50). The expansion of the gauzes to sector shape may be corrected when the liquid elastomer flows. FIG. 51 shows the state as the material flows into the mold. Numeral 212 represents a lower mold, 213 an upper mold, 214 a port for pouring the elastomer provided at the upper mold 213. When the upper and lower molds are tightened, the expansion of the gauzes is corrected and at the same time the liquid elastomer flows from the port 214, and the gauzes are fixed to a normal position. The roller is as shown in FIG. 52. Numeral 19 is the elastomer, 215 is the part corresponding to the rim, which is mounted on wheels similar to the solid tires to form the current collecting roller.

When the liquid elastomer flows between the gauzes, the electroconductivity between the lead wires composing the gauzes is eliminated due to insulting effect of the elastomer, but the electroconductivity is removed between metal gauzes by the spring function of the gauzes. However, it is free to conduct a dipping treatment for the gauzes such as with the electroconductive adhesive agent.

When the gauzes are superimposed, in order to reinforce against the centrifugal force and to effect a uniform current collecting function on the circular periphery of the roller, as shown in FIG. 53, one gauze is rotated or displaced by approximately 45° with respect to the other, and when sets of two gauzes are displaced several times to assemble a predetermined number thereof, desired characteristics of sets are obtained. The desired characteristics include less deformation due to centrifugal force and smooth rotation due to Young's modulus. When the gauzes are cut in circle, part of wires are loosened, or when they are assembled as the current collecting roller, the wires are thrown out by the centrifugal force. To avoid this problem, some of the wires are eliminated as shown in FIG. 54.

The current collecting rollers shown in FIGS. 49 and 52 are made by integrating the gauzes and the keep plates, and then the liquid elastomer flows therethrough.

5 The embodiment shown in FIGS. 55 and 56 is made by superimposing a predetermined number of gauzes, flowing the liquid elastomer under pressure up and down in the mold, and after solidification finishing it to a predetermined shape by cutting, grinding, etc. to 10 form a composite current collecting element, and mounting a rotary support thereto. When the liquid elastomer flows thereinto, each one is made by using circular gauzes and a circular mold. A composite material of gauze-elastomer may be made at one time to 15 form many current collecting elements therefrom.

In FIG. 55, numeral 216 represents the gauzes and 19 liquid elastomer. Numeral 217 represents a tapered hole provided at the center and 218 holes for mounting the rotary support. Normally, the grinding interference 20 on the outer periphery is retained at first, and a tapered hole such as 217 is formed at the center of the composite material of the gauze-elastomer which has been cut generally in a circle to form a composite current collecting element 229. The lead wires of the gauzes are 25 seen on the inner surface 219. The composite current collecting element 229 of the gauze-elastomer is fixed with the bolts 222 and the nuts 223 by the support 220 having a rotary shaft and annular projection 228 corresponding to the tapered hole provided at the current 30 collecting element 229. The support 221 is opposite to the support 220. After assembly, the outer peripheral surface 224 of the current collecting element 229 is ground to form a finished surface for the current collecting roller. Numeral 224 represents a rotary shaft of the rotary supports 220 and 221 to mount the bearings 225. The electric connection at the tapered portion 219 is obtained by fixing the composite current collecting element 229 rigidly to the rotary supports 220 and 35 221 by the bolts 222 and the nuts 223. The current collecting for the vehicle is conducted by pushing the current collecting shoe onto the end surfaces 225 and 226 of the rotary shaft. The electric connection of the lead wire portion 227 of the gauze to the annular projection 40 228 becomes more positive by using an electroconductive adhesive or metal foil conductor, or both on the tapered portion 219 to construct the current collecting roller having desired characteristics. The holes provided in the current collecting element 229 to fix the rotary support, are not necessarily tapered as shown in FIGS. 55 and 56; it may suffice if both the composite current collector and rotary support can be connected 45 mechanically as well as electrically.

55 Since the liquid elastomer is poured under pressure from the upper and the lower portions, the conductivity between gauzes does not decrease due to the elastomer insulating individual conductors, resulting in conductivity between the gauze positioned on both outer sides of the composite current collector and the optional gauze. Therefore, the assembly method such as shown in FIGS. 57 and 59 may be used. Numeral 230 is the lead wire ends exposed on the surface of the liquid elastomer.

60 Though in the embodiments shown in FIGS. 55 and 56 the electric connection of the composite current collecting element to the rotary support is conducted by providing a tapered irregular portion, other methods 65

such as burying the lead wires in the composite current collecting element may be used.

The current collecting roller utilizing the gauzes shown in FIGS. 48 to 56 are generally less expensive than the other current collecting roller, and are more uniform in density of the lead wires on the outer peripheral surface of the current collecting roller in the circular peripheral direction of the current collecting roller. However, the gauze roller is weak with respect to centrifugal force. Therefore, if a proper number of reinforcing discs of proper size (its outer diameter is smaller than that of the current collecting roller) are inserted between the gauzes, they may sufficiently strengthen the gauze against the centrifugal force, and may be useful for heat dissipation in the current collecting roller for enduring at higher speeds.

FIG. 57 shows the embodiment using reinforcing discs 231. The higher the speed of the roller becomes, the larger the centrifugal force becomes. In the examples shown in FIGS. 49, 52, 53, 54 and 56, the gauzes cut in coaxial circle are used, and the gauze therefore has many short lead wires which are not desirable with respect to the centrifugal force. For this reason, the embodiment shown in FIG. 57 has the gauzes extending to the center. Numeral 232 represents gauzes, 233 and 234 are opposite supports having a rotary shaft 235 and bearings 236. The manufacturing method of the current collecting roller shown in FIG. 57 comprises superimposing a predetermined number of the gauzes and the reinforcing discs, tightening the opposite supports from both sides thereof by using bolt 237A and nut 237 or a mold, then flowing the liquid elastomer 19 between the lead wires, the gauzes and the reinforcing discs, and between the opposite supports and the gauzes to provide a current collecting roller. To produce the embodiment shown in FIG. 56, the method comprises superimposing a predetermined number of the gauzes cut in circle and the reinforcing discs, flowing the liquid elastomer under pressure from both sides by utilizing the mold, etc., solidifying the elastomer between the gauzes and between the gauzes and the reinforcing discs to form a composite current collecting element, surface grinding to finish the parts 238 and 239 contacting with the opposite supports 233 and 234 shown in FIG. 57, if necessary, and tightening them by the bolts 236 ad the nuts 237 to obtain an electric connection of the lead wires of the gauzes to the opposite supports 236 and 237. When the composite current collecting elements are manufactured, considerable pressure is applied on both surfaces thereof to force flow of the liquid elastomer which is thereafter solidified. The electroconductivity between the gauzes, or between the gauzes and the reinforcing discs is not deteriorated by the spring action of the gauzes. In order to ease the flow of liquid elastomer and to reinforce it, holes may be properly formed at the reinforcing discs. It is also possible to provide peripheral grooves similar to that shown by 25 in FIG. 7 at the position of the reinforcing discs at the current collecting roller using the reinforcing discs. In case of the composite current collecting element, if the reinforcing discs are provided at both ends thereof, the assembling, and electrical and mechanical connections between the current collecting element and the rotary support, are improved.

FIG. 58 shows a composite current collecting element using two reinforcing discs 240 and 241. Numeral 242 represents gauzes in the center. The current col-

lecting element shown in FIG. 58 is manufactured by superimposing the reinforcing discs 240 and 241 at both sides of the several hundred of the gauzes, pressurizing the liquid elastomer to cause it to flow into the mold and then solidify. Holes for facilitating easy flow of the liquid elastomer may be provided, without trouble, in the reinforcing discs 240 and 241 of the current collecting element 243. The holes for mounting it to the rotary support may be provided by cutting after the liquid elastomer has flowed therein.

FIG. 59 shows the current collecting roller having three current collecting elements as above.

Numeral 243, 244 and 245 represent the current collecting elements, 246 and 247 are opposite rotary supports and 248 a rotary shaft. The current collecting elements 243, 244 and 245 are fixed by the bolts 249 and the nuts 249a from both sides thereof at the rotary supports 246 and 247. In this case, the current collecting roller is constructed by assembling three elements as shown in FIG. 59, and then grinding the outer peripheral surfaces thereof to a desired finish. An electric current flows from the lead wires on the exposed peripheral surface which contacts the rail, through the gauzes and reinforcing discs to the rotary support. In order to obtain a larger electric capacity, a larger number of current collecting elements are used.

In the aforementioned current collecting roller, it is desirable to make the lead wires in the lateral direction in contact with the outer peripheral surface of the roller, dense at both ends, and not as dense at the center thereof. This will now be described with reference to FIGS. 60 to 63.

As shown in FIG. 60, when the current collecting roller in which the resilient lead wires 250 are of uniform density at the peripheral surface 252 of the electroconductive rigid central support 251, the contacting pressure of the lead wires 250 becomes large at the center A and small at both sides B and C due to the lateral deformation of the lead wires and the elastomer between the leads as seen by a characteristic curve in the graph of contacting pressure in ordinate and of width of the fixed lead wires in abscissa in FIG. 61. D—D shows the amplitude of the required pressure for collecting current. Such irregularity of the contacting pressure produces the difference in the contacting resistance so that the current at the center becomes larger than that at both sides thereof with the result that the total surface of the current collecting roller is not used effectively and the current collecting efficiency decreases.

Numeral 256 represents the part of the shaft of the electroconductive rigid central support and 257 represents bearings. 16 is a cylindrical current collecting surface.

In order to improve upon the aforementioned disadvantages, the number of resilient lead wires fixed onto the peripheral surface of the electroconductive rigid central support are arranged with the density at the edges greater than the density in the center. The liquid elastomer flows between the lead wires and is solidified to form an integral current collecting roller. This is shown by FIG. 62, wherein the same numerals as those shown in FIGS. 60 and 61 designate the same parts.

Numeral 253 and 254 represent both side parts having a greater density of the resilient lead wire 250, and 255 is the part having relatively small density of the lead wires at the center. The current collecting roller is made by flowing the liquid elastomer between the

lead wires, then solidifying the elastomer to form an integral structure. As a result, the contacting pressure between the current collecting roller and the current collecting wires becomes generally uniform at both sides B and C and at the center A under pressure as shown in FIG. 63.

In the foregoing description, in the current collecting roller utilizing the gauzes, small mesh, broadpitch gauzes are disposed at the center, as in FIG. 7, it is easily constructed by changing the diameter or pitch of the holes through which the lead wire bundles are inserted in the discs.

The performance of the current collecting roller may be expressed by the current carrying capacity or how much the electric current can flow therethrough. More particularly, the electric current is increased while all the conditions except the current such as speed are made constant. A spark is generated between the current collecting wire or feeder line and the current collecting roller from a certain amount of current as the current is increased. As the current is increased further, this spark becomes arc, in which state, if it is not corrected, the conductor exposed on the cylindrical current collecting surface of the current collecting roller is damaged by the arc and becomes unuseable. For this reason, over-current for generating the arc cannot be used. The current capacity depends, of course, greatly upon the structure of the current collecting roller, but it also depends upon the following two factors: the speed and the load for pushing the current collecting roller onto the feeder line or current collecting line. Particularly, it depends greatly upon the pushing load. Several embodiments and examples of experiments will now be described in the following:

An experiment was conducted such that the part corresponding to the feeder line or current collecting wires was a wheel, and while this was rotating, the current collecting roller is pushed onto the wheel (Rotary tester).

The current collecting roller used corresponding to that shown in FIG. 17 is as follows:

Outer diameter of roller:	200mm
Outer diameter of lead wires:	0.43mm
Total number of lead wires exposed on the cylindrical current collecting surface:	4440 pieces
Density of lead wires (mean):	7.1 piece/1mm in periphery
Elastomer:	urethane rubber of hardness of 68
Width of current collecting surface:	44mm

Using this with a pushing load of 33Kg, peripheral speed being 100Km/hr., at least 30 amperes of current capacity could be taken out.

The current collecting roller corresponding to that shown in FIG. 2 is as follows:

Outer diameter of current collecting roller:	200mm
Outer diameter of lead wires:	0.3mm
Total number of lead wires exposed on the cylindrical current collecting surface:	13,200 pieces
Density of lead wires (mean):	21 pieces/1mm in periphery
Elastomer:	Urethane rubber of hardness of 90
Width of current collecting surface:	29mm

Using this with a pushing load of 75Kg, peripheral speed being 250Km/hr., at least 120 amperes of current capacity could be obtained.

Using the current collecting roller corresponding to that shown in FIG. 58.

Outer diameter of current collecting roller:	200mm
The gauzes used:	16 mesh - 44
Outer diameter of lead wires:	0.304mm
Resilient material:	Urethane rubber
Width of current collecting surface:	20mm
Outer diameter of reinforcing plates:	166mm

Using this with a pushing load of 80 Kg, peripheral speed being 300Km/hr., at least 150 amperes of current capacity could be obtained.

FIG. 64 shows one embodiment of a transportation apparatus using a current collecting roller according to the present invention.

As shown in FIG. 64, a roller current collecting apparatus has a DC linear motor having stationary armature windings 258 and 259 arranged stationarily on ground positions vertically with respect to the ground and linearly adjacent thereto with a power supply loop to produce magnetic flux 262 crossed with both the conductors in horizontal and vertical directions. Shifting magnetic field winding 261, movable in longitudinal direction 273, with respect to the stationary armature winding 258 and 259 is disposed linearly, two positive and negative feeder rails 263 and 264 for feeding current in connection to the positive and negative terminals 270 and 271 of DC power supply 269 are provided stationarily in longitudinal direction of the stationary armature windings 258 and 259. The current collecting rails 265 and 266 are arranged with the conductor having a length corresponding to the pitch of the stationary armature windings 258 and 259 at proper linear intervals and in two rows and connected with both ends of the stationary armature windings 258 and 259 to the respective conductors thereof. Current collecting rollers 267 and 268 are movable together with the movable magnetic field winding 261 while rotating in contact with the positive and negative feeder rails 263 and 264 and the current collecting rails 265 and 266 interleaved therebetween for supplying current 260 to predetermined stationary armature windings 258 and 259. The movable magnetic field winding 261 is loaded on the vehicle to magnetically float the vehicle and at the same time to directly drive the vehicle.

The current collecting roller used as shown in FIG. 64 requires a broad width of current collecting surface such as shown in FIG. 59. In the current collecting roller as shown in FIG. 59, if composite current collecting elements 243, 244 and 245 are mounted in large numbers, a desired purpose may be performed. The current collecting roller used as shown in FIG. 64 is not strictly used for current collection as the required power supply on the vehicle. That is, the necessity for taking electricity for the vehicle from the end surface of the rotary shaft of the current collecting roller is eliminated as shown in FIG. 64. However, in FIG. 64, if the movable magnetic field (provided on the vehicle 261) is by electromagnet, the electricity therefor must be collected, but in such case, current collector such as used in an electric motor at the end (for example, by 225 and

226 in FIG. 56) of the rotary shaft of the current collecting roller is pushed to collect the current.

We claim:

1. A current collecting roller having a cylindrical current collecting surface and comprising:

- a. conductor means comprising a plurality of flexible conductors positioned in said roller at least in the proximity of said surface thereof for collecting current from a trolley wire;
- b. an elastomer filling the spaces between said conductor and forming the body of said roller;
- c. the ends of said conductors extending to said cylindrical surface, so that said elastomer and the outer ends of said conductors form said cylindrical current collecting surface; and
- d. shaft means for mechanically supporting said roller body, said shaft means being disposed centrally of said roller body and being electrically connected to said plurality of conductors.

2. The current collecting roller as set forth in claim 1, wherein said conductor means further comprises a plurality of superimposed gauze means, each gauze means comprising a mesh of electroconductive wires; and further comprising keep plate means on each side of said plurality of gauze means and fixed to said shaft means for clamping said plurality of gauze means tightly together, wherein said elastomer is between each of said gauze means and between said gauze means and said keep plate means such that the current collecting surface is formed at one end of said electroconductive wires of said gauze means.

3. A current collecting roller as defined in claim 1 wherein said elastomer is polyurethane.

4. A current collecting roller as defined in claim 2 wherein each gauze means is in the form of an annulus.

5. A current collecting roller as defined in claim 2 further comprising a rigid reinforcing disc disposed between an adjacent pair of said gauze means and clamped by said keep plate means, said reinforcing disc having a smaller diameter than that of said roller.

6. A current collecting roller as defined in claim 2 further comprising a pair of rigid reinforcing discs disposed on either side of said body and clamped by said keep plate means, said reinforcing discs having diameters smaller than that of said roller.

7. The current collecting roller as set forth in claim 1, wherein said conductor means comprises a plurality of electroconductive discs, each disc having a plurality of holes formed near the peripheral edges thereof with said conductors inserted through said holes in said disc in such a manner that both ends of the conductors are directed outwardly forming a U shape, wherein said plurality of said discs are superimposed upon each other and wherein said elastomer is between said conductive discs and said conductors such that the cylindrical current collecting surface is formed by both outer ends of each of said conductors.

8. The current collecting roller as set forth in claim 7, further including push plate means for effecting electroconductivity between said conductors and said electroconductive discs, and for reinforcing the roller against the centrifugal force while dissipating heat therein.

9. The current collecting roller as set forth in claim 8, wherein the distances between the electroconductive discs and between the discs and the push plate means

gradually decrease toward the outer periphery of the roller.

10. The current collecting roller as set forth in claim 8, wherein said electroconductive discs are bent on their outer peripheral portion.

11. The current collecting roller as set forth in claim 1, wherein said conductor means comprises a plurality of electroconductive rings with said conductors contacting each said ring in such a manner that both ends thereof are directed outwardly forming a U shape, wherein said rings are supported on said shaft means, wherein said elastomer is between the conductors such that the cylindrical current collecting surface is formed by both outer ends of said conductors.

15 12. The current collecting roller as set forth in claim 1, wherein said conductor means comprises electroconductive rod fixed uniformly near the peripheral edges of the side portion of said shaft means; with said conductors forming a U shape and engaging said rod

20 and a keep ring for fixing the other end of said rod to said shaft means wherein the elastomer is between said conductors and the cylindrical current collecting surface is formed by both outer ends of each of said conductors.

25 13. The current collecting roller as set forth in claim 1, wherein said conductor means comprises belt means implanted with said conductors, said belt means surrounding said shaft means wherein said elastomer is between said conductors such that the current collecting surface is formed at the ends of said conductors.

30 14. The current collecting roller as set forth in claim 1, wherein said conductor means comprises a resilient support positioned around said shaft means, and a belt means implanted with said conductors and surrounding an electroconductive outer support wherein said elastomer is between said conductors such that the current collecting surface is formed by the outer ends of the conductors.

35 15. The current collecting roller as set forth in claim 1, wherein said conductors are non-linear conductors are used as linear conductors.

40 16. The current collecting roller as set forth in claim 1, wherein said conductor are in the form of a plurality of conductive foil members, each foil member having an upper and lower portion, said upper portion including a plurality of projections and said lower portion including an engaging means; and a plurality of spacer means, said spacer means being positioned between the lower portions of said conductive foil members in an alternate manner wherein said spacer means includes engaging means corresponding to the engaging means of said foil members wherein said elastomer is between the upper portions of said conductive foil members thereby laminating said foil members and the cylindrical current collecting surface is formed at the ends of said projections, said shaft means comprising retaining means for cooperating with the aforesaid engaging means to secure said foil members and said spacer means to said shaft means.

45 17. The current collecting roller as set forth in claim 16, wherein each of said spacer means is a conductive foil.

50 18. The current collecting roller as set forth in claim 16, wherein each of said spacer means is an insulating foil.

55 19. The current collecting roller as set forth in claim 1, wherein said conductors are in the form of a plurality

23

of conductive foil members, each foil member having an upper and lower portion, said upper portion including a plurality of projections and said lower portion including engaging means and separating means, wherein said foil members are positioned adjacent each other but substantially separated by said separating means and wherein said elastomer is between the separated portions of said foil members and the cylindrical current collecting surface is formed at the ends of said projections, said shaft means comprising retaining means

10

24

for cooperating with said engaging means to secure said foil members to said shaft means.

20. The current collecting roller as set forth in claim 19, wherein said separating means are projections formed on said lower portion.

21. The current collecting roller as set forth in claim 1, wherein the density of said conductors is greater at the sides of said roller than at the center thereof.
